UNITED STATES PATENT OFFICE.

BENJAMIN W. TUCKER, OF SOUTH ORANGE, NEW JERSEY, AND JAMES A. EKIN CRISWELL, OF BROOKLYN, NEW YORK, ASSIGNEES TO CORONA TYPEWRITER COMPANY, INC., A CORPORATION OF NEW YORK.

TYPE-WRITING MACHINE.

1,281,102.

Specification of Letters Patent.

Patented Oct. 8, 1918.

Application filed January 6, 1916. Serial No. 70,611.

To all whom it may concern:

Be it known that we, BENJAMIN W. TUCKER and JAMES A. EKIN CRISWELL, citizens of the United States, and residents of 5 South Orange, county of Essex, and State of New Jersey, and of the borough of Brooklyn, county of Kings, city and State of New York, respectively, have invented certain new and useful Improvements in 10 Type-Writing Machines, of which the following is a full, clear, and exact description. This invention relates more particularly to the carriages of typewriting machines. One of the principal objects of the invention 15 is to provide a carriage having a platen wherein the platen may be positively supported at its ends and made extensible in order that wide sheets of paper, large envelopes or other work may be properly supported to be written upon, thus providing a carriage which may be shortened or lengthened at will and thereby avoiding the necessity for providing interchangeable carriages and at the same time overcoming 20 many of the objections incident to carriages as ordinarily constructed.

Another object of the invention is to provide a carriage for writing machines wherein in the platen and supporting parts therefor 25 may be simultaneously extended at both ends so that the work sheet may be properly centralized with respect to the type and the feed of the carriage.

Other objects of the invention are to provide 30 a carriage whereby the carriage base as well as the ends supporting the platen may be extended on either or both sides to lengthen materially the carriage to adapt the machine for wide paper, large envelopes, etc., to provide means whereby the carriage and parts thereof, as the escapement release 35 and paper feed release, may be operated notwithstanding the extensibility of the carriage without materially complicating the construction or operation of the parts; to provide simple means whereby the line-spacing mechanism may be extended as the platen and its supporting base are extended; and to provide simple means whereby the 40 extension of one end of the platen carriage will automatically extend the other end.

Another object of the invention is to provide simple and efficient means whereby a substantially rigid and extensible support-

ing means is provided for the platen; and 55 to provide simple and efficient means whereby the extensible part of the platen carriage may be locked in any one of its adjusted positions.

A still further object of the invention is 60 to provide a carriage which may be readily applied to typewriting machines of ordinary construction.

A still further object of the invention is 65 to provide an extensible platen carriage which may be readily made and assembled.

With these and other objects in view, the invention will be hereinafter more particularly described with reference to the accompanying drawings, which form a part 70 of this application, and will then be pointed out in the claims at the end of the description.

In the drawings, Figure 1 is a plan view broken away centrally thereof of one form 75 of platen carriage embodying the invention.

Fig. 2 is a front elevation.

Fig. 3 is an end elevation.

Fig. 4 is a vertical transverse section showing one form of line-spacing mechanism, the section being taken on the line IV—IV of Figs. 1 and 2.

Fig. 5 is an enlarged vertical transverse section taken on the line V—V of Fig. 7.

Fig. 6 is an end view of the platen carriage looking in the direction opposite to that shown in Fig. 3.

Fig. 7 is an enlarged longitudinal section, the platen and carriage being shown shorter than ordinarily used for the purpose of better illustration.

Fig. 8 is a fragmentary longitudinal section on a smaller scale of the platen in an extended condition.

Fig. 9 is a fragmentary section through a 95 part of the carriage base, showing how the extensible parts may be locked in various adjusted positions.

Fig. 10 is a fragmentary view showing one form of escapement release; and 100

Fig. 11 is an end view of the parts shown in Fig. 10.

While the invention is shown as constructed for use in connection with the Corona portable and foldable typewriter, it 105 will be understood that the construction may be changed to adapt the invention with the extensible feature to be employed on

writing machines of various kinds and constructions.

The carriage 10 has a base 11 which is adapted to travel along a carriage bed under the control of suitable escapement mechanism in the usual or in any preferred way. This base 11 has a relatively fixed member 12 of a plate-like form and of any desired length, and above the base portion of the member 12 are two slidable members 13 and 14. The members 13 and 14 form an extensible means for the base and are located adjacent to each other to adapt one partly to support and guide the other. The base member 12 has upwardly extending flanges or walls 15 which form side guides and supports for flanges or walls 16 of the slide member 14, said walls or the sides 16 being bent over at the upper portion to ride along the upper edge of the walls 15. The slide member 13 is provided with upwardly extending walls 17 adapted to rest against the inner face of the walls 16 and said walls 17 have their upper ends extending outward angularly with respect to the vertical portion. A substantially L-shaped member or plate 18 is secured to each wall 15 of the base member 12 and has the upper angular portion thereof extending inward over the upper end of the walls 16 and under the outwardly extending angular portion of the walls 17 of the member 13. These members 18 serve as retaining means and also as separating means for the members 13 and 14 to permit the latter to be extended relatively to each other as will be presently described. A member 19 substantially the same form as the base member 12 but inverted with respect thereto fits about the outer walls of the several members and serves to inclose the same forming a support for certain parts of the carriage. The member 19 has marginal lengthwise and downwardly extending walls 20. These walls together with the members 18 and the walls 15 are secured together and the said members 12, 18 and 19 remain in a normally fixed position with respect to the members 13 and 14. By this means a strong light base is provided whereby certain members thereof may have a sliding movement relatively to the other members.

On one of the slide members of the base, as 13 for example, is held a supporting end or bracket 21, while on the member 14 at the opposite end of the carriage is securely held an end or bracket 22. The ends 21 and 22 by reason of the slidability of the members 13 and 14 may be moved toward or from each other and may be moved so as to extend the base of the carriage independently or in unison as preferred. As shown, means is provided whereby on the movement of one end and one slide member of the carriage, the other slide member and the other

end or bracket 21 is moved in unison in an opposite direction, thus simultaneously extending both supporting ends or brackets. As one means to secure the extension of both ends, one member, as the member 13, has a rack 23 held thereto to move therewith and to the other slide member 14 of the base a rack 24 is held. These racks are of any desired length and may be constructed to be light and strong. Arranged substantially central of the carriage is a pinion 25 supported to rotate on the relatively fixed base member 12, and having its teeth adapted to engage the teeth of the racks 23 and 24. It will thus be evident that by moving either of the ends or brackets 21 and 22, a similar extension movement will be given to the opposite end and in unison so that both ends or brackets 21 and 22 will be moved the same extent from opposite ends of the base in order that the carriage may be adapted for extra widths of work sheets.

A platen 26 is rotatably held in the end brackets 21 and 22 of the carriage and is also constructed to be extended and be rotatably supported at its ends in all adjustments of the brackets 21 and 22. The platen comprises an impact member 27 in the form of a circular roll of rubber or other material, and arranged within said member 27 is a tubular mounting 28 of metal or other material adapted properly to support the impact member 27. At each end of the member 27 and held to slide lengthwise thereof is a tubular or other member 29 and movable within the member 29 is still another tubular or other member 30. The member 30 is provided with a slot 31 in which a pin 32 secured to the tubular member 29 is adapted to slide, and said tubular member 29 is similarly held by a pin and slot connection, as 32^a and 32^b respectively, with the relatively fixed mounting member 28. At the outer ends of each of the tubes 30 is a bushing 33 and this bushing is provided with a stem 110 or stud 34 one for each of the ends 21 and 22. These studs are in axial alinement so that whatever their position they will rotatably hold the platen and sustain the same so that it will rotate true and properly in said bracket, there being on one or both of the studs 34 a knob 35 by which the platen may be rotated by the operator. As the platen is held between the ends or brackets 21 and 22, it will be evident that on the movement of said ends 21 and 22 as previously described, the inner tubular members 30 will permit an extension of the platen a certain distance until the pins 32 at each end of the platen reach the ends of the slots 115 31 and when this takes place, the intermediate tubes 29 will move in unison with the tubular members 30 serving to give a further extension at each end of the platen if such extension is desired or necessary, it being 120 125 130

understood that only one tube or more than two tubes may be used at each end of the platen to get greater or less extension than shown, if desirable.

5 To automatically extend the platen at both ends various means may be employed. As shown, the inner telescopic tube 30 or other member has a rack 36 held thereto which extends lengthwise of the platen, and 10 held to the other tube or member 30, at the opposite end of the platen, is a rack 37. The teeth of these racks extend inwardly and are formed on curved segmental guiding portions 38 which are opposed to each 15 other and are guided within the platen body. The teeth of the racks 36 and 37 are engaged by a pinion 40 substantially centrally of the platen so that when either one of the ends 21 and 22 is extended as already 20 described the telescopic or collapsing members of the platen will also be extended and as one of the racks is moved the other rack is also moved, but in an opposite direction, thus forcing the opposite ends of the platen 25 inwardly or outwardly, according to which direction the platen support ends are moved, and whether or not the platen and carriage are to be extended or shortened. At the center of the platen and within the same is a 30 filler block or member 41. This block 41 serves as a guide and also a stop against which the ends of the tubes 29 and 30 may rest when the platen is in its shortest condition, and this block or member 41 conforms 35 to the cylindrical shape of the mounting 28 forming with the impact member 27 the main body of the platen. The pinion 40 is rotatably held in a block 42 which may be secured to or formed integral with the member 41. As thus shown, both ends of the platen are extended or shortened in unison, though it will be understood that other means than the rack and pinions may be employed for this purpose or the platen may 45 have either or both ends extended independently, this being the case also with respect to the carriage wherein substantially similar means is shown for moving both ends of the carriage. The pinions 25 and 40 and the 50 racks are similarly constructed so that the ends 21 and 22 as well as the extensible features of the platen may move to the same extent and in unison.

The platen may have suitable paper fingers as 43. These paper fingers may be supported to move lengthwise of the carriage, as usual. A bar 44 is provided for that purpose, and each paper finger has a substantially U-shaped part 45 forming a slide and guide for the paper fingers. Extending upwardly from the guide 45 is a spring portion 46 having its upper end provided with inwardly extending lugs or parts 47 in which is rotatably held a roll 48 to assist in holding the work to the platen body. A plu-

rality of paper fingers 49 may also be used when the platen and carriage are extended to assist in holding and guiding the work properly, particularly where wide sheets or wide envelopes or other work are written upon. As shown, two paper fingers are provided and these may be permanently attached to the front walls 16 and 17 of the extensible base members 14 and 13 respectively, so as to move with said members when said members are extended or collapsed. The fingers 49 are constructed similar to the fingers 46 except that they remain in a fixed position so far as independent relative movement is concerned, and each finger 50 co-operates with a platen section 50. Each section 50 forms in substance an end of the platen body and is adapted to be moved toward and from said body to shorten and lengthen the platen. The sections 50 at the 85 opposite ends of the platen are similarly constructed to the body 27 and are supported on the inner telescopic tubes or members 30 so as to move therewith. The purpose of the platen ends or sections 50 is to support 90 the outer ends of wide sheets of paper, envelopes, or other work held to the main body of the platen. These sections also assist in the proper movement of the work with the platen during the line-spacing and letter feed movement thereof. Each platen section 50 may have a rubber or other disk-like portion 51 mounted upon a cylindrical part or section 52, the latter being held to or formed as a part of the bushing or part 33. The 100 part or section 52 may be cut away so that the outer end of the tube 29 may move partly into the bushing or mounting 52 at each end of the platen.

As a means for locking the base members 105 and the platen in the different adjusted positions, various means may be employed. As shown a dog or latch 53 is provided which is suitably located within the base of the carriage above the member 13 and under the 110 normally fixed base member 19. This dog or latch 53 may be held to a rod 54 which is normally forced in one direction by means of a spring 55 so as to force the dog normally to a locking position. The dog has a tooth 115 or end 56 which is adapted to enter apertures 56 or slots as preferred which may be cut out of the base members 13 and 14 and are so arranged that when the apertures of said members register, the tooth 56 may enter said apertures and lock the plates or base members 13 and 14 against further movement. A lever 57 is held to one end of the rod 54 and to the other end of said lever is a finger portion 58 by which the dog may be 125 released when the lever 57 is moved by the operator during the extension or collapsing of the carriage and platen. By this means both the platen and the carriage are positively locked in any one of their adjusted 130

positions, and by reason of the racks and pinions all parts are locked against free relative movement until released.

The carriage is so constructed that it may be provided with the usual parts and attachments which coöperate with and usually form a part of the carriage without affecting the adjustability of the platen and carriage or either of them. The main inclosing normally fixed member 19 may support the parts of tabulating mechanism, as well as the marginal stops, line-lock mechanism, and other features, and may also serve as a support for a paper apron 59. The paper apron and means for mounting the same are substantially similar to that disclosed in the Corona typewriter. As shown, the apron is formed of a curved plate 60 which has depressed portions as 61 adapted to engage studs 61^a on the base member 19, and serve as a pivot for said apron. At the forward portion of the paper apron parts thereof are depressed to provide a bearing for feed and pressure rolls 62, the latter being of the usual or any preferred construction, and are adapted to assist in feeding the work about the platen during the rotary movement thereof. A scale 63 may be supported by the outer end of the paper apron as usual, and said paper apron may be normally forced in a direction to cause the roll or rolls 62 to press against the platen body by means of a spring 64 or otherwise, one end of which is attached at the rear of the paper apron, and the other end to a lug or projection on the base member 19. The paper apron may be released by means of a lengthwise extending bar 65, one end of which is provided with a finger portion 66 to engage the under part of the paper apron body 59. The bar 65 is suitably supported under the paper apron and at one end thereof is provided with an outwardly extending handle as 67 in convenient reach for the operator whereby the operator may release the pressure roll to adjust the work on the platen.

In addition to the knob 35 as means for rotating the platen and the extension sections thereof, suitable line-spacing mechanism is provided. The line-spacing mechanism may be substantially identical with the construction on the Corona typewriter referred to, the construction and mounting being such however that said line spacing mechanism is always accessible to the operator in any of the extended positions of the carriage and platen or either of them, it being broadly new so far as applicants are aware to so mount a line-spacing mechanism of any construction. On the left hand stud 34 of the platen, adjacent to the end section 50 on that side of the carriage, is a toothed wheel 68. This toothed wheel is fixed to rotate with the platen and is normally held against movement by a roll 69

arranged upon an arm 70, Figs. 3 and 4, which is pivoted at 71 to the end or bracket 22 of the carriage, a lever 72 being provided to release the roll from the toothed wheel when desired. A hand-operated lever 73 is mounted upon the stud 34 and carried by said lever is a pawl 74, which is adapted to engage the teeth of the wheel 68. A pin 75 is provided on one end of the lever, and an adjustable stop 76 is arranged on the other side of the lever between which two stops the lever 73 is adapted to move. The stop 76 is normally held in its adjusted position by a spring 77 and may be rotated by means of a knob 78. The pawl is normally forced into an engaging position by means of a spring 79 carried by the lever 73, and in the position shown in Fig. 3 is normally disengaged from the teeth by means of the pin 75 with which it contacts. The stop 76 limits the forward movement of the pawl and lever and determines the extent of movement of the platen for line-spacing as is usual, there being a spring, not shown, for restoring the lever 73 and pawl to its normal position. As thus constructed, the line-spacing may be variously arranged to move the platen on its axis for different line-spacing movement, and the entire line-spacing mechanism partakes of the extension of the platen and the carriage.

The carriage may also have means whereby the escapement may be released to permit the carriage to be moved freely forward or backward independently of the escapement mechanism. The escapement mechanism except so far as the rack is concerned is not shown, as it forms no part of the present invention, but may include a dog carrier or other means whereby the carriage may be released. As one means and as a part of the escapement mechanism, a rack 79 is shown under the base member 12 and supported under the carriage is a tappet bar or part 80. The bar 80 is adapted to be given an inward movement by means of a forwardly extending lever 81 on the forward end of which is a finger portion 82 so that on the movement of the lever the escapement dogs may be released from the rack 68.

The carriage is adapted to be guided along a carriage bed, not shown, and as in the Corona typewriter a rail as 83 is provided at the rear of the carriage as one guiding means and at the forward part of the carriage is a plate 84 forming a part of a raceway or other guiding means to assist in supporting and holding the carriage in its letter-spacing movement along the bed, though it will be understood that the construction of these features as well as some of the others will vary according to the construction of the carriage and the particular machine in connection with which the carriage is used.

It will be understood that the platen may

be constructed so that it will be light and strong and yet not affect its writing characteristics; and that the platen may have more than one pressure roll coöperating therewith 5 and so disposed as will assist in the proper holding of the work and also in the proper alinement and working of the platen.

It will be further understood that rolls or disks forming extension sections of the 10 platen and of the same diameter may be held to the outer ends of the tubes 29 or otherwise as a further means to assist in supporting the work intermediate the main body of the platen and the end sections. If desired the 15 rack may be made in a plurality of sections which are adapted to register properly and which permit the carriage to travel substantially the length of said carriage when extended. In this latter case the platen itself 20 may be of the construction shown or longer and interchangeable rolls may be used, or other extension means as rods or tubes, or separate roll sections corresponding to the extension of the carriage may be employed. 25 It will be evident from the foregoing that effective means is provided whereby the platen and carriage or either of them may be extended to adapt wide sheets or envelopes to be written upon; that the work is properly supported; that simple means is provided whereby the work may be held substantially throughout its length; that simple 30 means is provided whereby the parts may be effectually locked in any of the adjusted 35 positions; that the adjustability of the carriage and platen or either of them does not affect the use of the coöperating parts usually employed in connection with a carriage; that the adjustability and extensibility of 40 the carriage are such that the carriage and platen or other work-holding means may be applied to carriages and machines of various constructions; and that the invention is simple in construction and may be readily made 45 and assembled.

Having thus described our invention, we claim as new and desire to secure by Letters Patent:—

1. In a typewriting machine, the combination of supporting means, a platen rotatably supported at its ends in said supporting means, and means whereby the supporting means may be extended to increase or decrease the distance between the end supports 55 of said platen.

2. In a typewriting machine, the combination of supporting means, an extensible work-sheet supporting roll rotatably supported at its ends in said supporting means, 60 and means whereby the supporting means may be extended to increase or decrease the distance between the end supports of said work-sheet supporting roll.

3. In a typewriting machine, the combination of supporting means, and an extensible 65

work-sheet supporting roll rotatably supported at its ends in said supporting means.

4. In a typewriting machine, the combination of supporting means, a work-sheet supporting roll rotatably supported at its ends 70 in said supporting means, and means whereby the supporting means and the roll may be simultaneously extended to increase or decrease the distance between the end supports of said roll.

5. In a typewriting machine, the combination of a base member, two relatively lengthwise movable members guided on said base member, means whereby said members may be extended or collapsed, ends held to the 80 lengthwise movable members, a work-sheet supporting roll journaled in said ends, means whereby the ends may be moved in unison, and telescopic means adapted to be moved in unison in opposite directions and 85 forming means to lengthen or shorten the roll.

6. In a typewriting machine, the combination of a base having relatively lengthwise movable members, means whereby said members may be extended or collapsed, ends held to the extensible members, a paper holding means journaled in said ends, and telescopic means adapted to be moved in opposite directions and forming means 90 to lengthen or shorten the paper-holding means.

7. In a typewriting machine, the combination of a base having a relatively fixed and two relatively lengthwise members guided 100 on said fixed member, means whereby said movable members may be extended or collapsed, a paper holding means journaled at its ends on said base, and telescopic means to lengthen or shorten the paper-holding 105 means.

8. In a typewriting machine, a carriage having relatively movable members to adapt the carriage to be lengthened or shortened, platen supporting means carried by said 110 members, and a platen rotatably mounted in said supporting means and having its support maintained in all positions of said members.

9. In a typewriting machine, a carriage 115 having relatively movable members to adapt the carriage to be lengthened or shortened, and an extensible work-sheet supporting roll supported in the carriage.

10. In a typewriting machine, a carriage 120 having movable end members to adapt the carriage to be lengthened or shortened, and a platen supported in said end members.

11. In a typewriting machine, a platen carriage having extensible supporting ends, 125 and an extensible work sheet supporting roll rotatably held in said ends and having a portion adapted to receive the impact of the type.

12. In a typewriting machine, a carriage, 130

- and a platen rotatably mounted thereon and comprising a roll, a plurality of tubular extensible members at each end of said roll, one of said members at each end being rotatably held in the carriage, means whereby the roll may be rotated, and means whereby the extensible members may be moved in unison.
13. In a typewriting machine, a carriage, and a platen rotatably mounted thereon and comprising a cylinder, extensible means at each end of said cylinder to hold the platen in the carriage, and means maintained in cooperative relation to said extensible means whereby the platen may be rotated.
14. In a typewriting machine, a carriage having a platen rotatably mounted thereon, said platen comprising a roll, a plurality of tubular extensible members at each end of said roll, one of said members at each end being rotatably held in the carriage, and means whereby the extensible members may be moved in unison.
15. In a typewriting machine, a carriage, a platen rotatably mounted thereon, feed means about the platen, and means whereby the platen structure and carriage may be extended.
16. In a typewriting machine, the combination of a carriage base, ends projecting upwardly from said base, a work-sheet supporting roll comprising an impact cylindrical member, telescopic tubular members arranged at each end of the impact member, said telescopic members being connected to adapt said members to be extended or telescoped to shorten or lengthen the roll, a rack secured to one of the telescopic members, a second rack secured to another telescopic member at the opposite end of the platen, a pinion in mesh with both racks to adapt the telescopic members to be moved in unison, and means whereby the roll may be rotated.
17. In a typewriting machine, the combination of a carriage base, ends projecting upwardly from said base, a platen structure comprising an impact cylindrical member, telescopic tubular members arranged at each end of the impact member and forming a support for the platen structure, said telescopic members being connected to adapt said members to be extended or telescoped to shorten or lengthen the platen structure, and means for moving the telescopic members in unison.
18. In a typewriting machine, the combination of an extensible carriage base, ends projecting upwardly from said base, a platen structure comprising an impact cylindrical member, means to adapt the platen structure to be extended or shortened, and rack and pinion means for simultaneously lengthening both ends of the platen structure.
19. In a typewriting machine, the combination of a carriage base, ends projecting upwardly from said base, a platen roll rotatably held in the ends and comprising an impact cylindrical member, relatively movable members arranged at each end of the impact member, said members being connected to adapt them to be extended or collapsed to shorten or lengthen the platen roll, a rack secured to one of the members, a second rack secured to another member at the opposite end of the platen roll, and a pinion in mesh with both racks to adapt the members to be moved in unison. 70
20. In a typewriting machine, a platen carriage having a base, ends extending upwardly from said base, means whereby the base may be variously extended or shortened, means for locking the base in any one of the adjusted positions, a platen roll rotatably supported in said ends, line-spacing mechanism mounted to move with the ends when the base is extended or shortened, and telescopic connections whereby the platen roll may be extended and supported at its 75 ends. 80
21. In a typewriting machine, a platen carriage having a base, a platen rotatably supported on the base, means whereby the base may be extended or shortened, and means for locking the base in its extended or shortened positions. 85
22. In a typewriting machine, a platen carriage having a base, ends extending upwardly from said base, means whereby the base may be extended or shortened, a platen rotatably supported in said ends, and line-spacing mechanism mounted to move with one of the ends when the base is extended or shortened. 90
23. In a typewriting machine, a platen carriage having a base, means whereby the base may be extended or shortened, means for locking the base in any one of the adjusted positions, a platen rotatably supported on said base, and line-spacing mechanism mounted to move when the base is extended or shortened. 95
24. In a typewriting machine, the combination of extensible supporting means, an extensible platen roll rotatably held in said supporting means and having a work-supporting impact member, and extensible sections adapted to support the outer edges of the work. 100
25. In a typewriting machine, the combination of supporting means, a platen roll rotatably held in said supporting means and having a relatively fixed work-supporting impact member, and extensible end sections adapted to support the outer edges of the work. 110
26. In a typewriting machine, the combination of extensible supporting means, and a platen roll rotatably held in said support- 120
- 125
- 130

ing means and having extensible end sections adapted to support the outer edges of the work.

27. In a typewriting machine, the combination of extensible supporting means, and an extensible platen roll rotatably held in said supporting means and having a work-supporting impact member, and extensible sections adapted to support the outer edges of the work and movable during the extension of said platen roll.

28. In a typewriting machine, the combination of an extensible base having a plurality of members, an extensible platen structure supported by said base, and a dog engaging parts of the base to lock the same in its adjusted position.

29. In a typewriting machine, the combination of an extensible base having a plurality of adjustable members, a platen supported on said base, and a dog engaging parts of the base to lock the same in its adjusted position.

30. In a typewriting machine, the combination of an extensible carriage base having a plurality of members, means for supporting work, a pivotally held dog engaging parts of the base to lock the same in its adjusted position, and a lever for moving said dog.

31. In a typewriting machine, a carriage having a relatively fixed member provided with a rack to adapt the carriage to be moved along its bed, two oppositely movable plate-like adjustable members guided to move lengthwise of said relatively fixed member, a rack secured to one of the adjustable members, a second rack secured to another adjustable member, a pinion engaging the racks to move the same in opposite directions and in unison, and means for locking the lengthwise movable members in their adjusted positions.

32. In a typewriting machine, a carriage having a relatively fixed member and adapted to be moved along a bed, two oppositely moving plate-like adjustable members guided to move lengthwise of said relatively fixed member, a rack secured to one of the adjustable members, a second rack secured to another adjustable member, and a pinion to cause the racks to move in opposite directions and in unison.

33. In a typewriting machine, a platen carriage having a relatively fixed member, two oppositely moving plate-like adjustable members guided to move lengthwise of said relatively fixed member, means for moving said plate-like members lengthwise, and means for locking the lengthwise movable members in various adjusted positions.

34. In a typewriting machine, a carriage having a base member adapted for supporting two lengthwise movable plate-like slideable members, brackets arranged on said

slidable members, means whereby the slideable members may be guided and held, and means supported in the ends of the brackets for holding the work sheet.

35. In a typewriting machine, a carriage having a base member, two lengthwise movable plate-like slideable members, means whereby the slideable members may be guided and held, and means supported by the carriage for holding a work sheet.

36. In a typewriting machine, a carriage base comprising a relatively fixed member having marginal upwardly extending walls lengthwise thereof, two plate-like slideable members movable relatively to the first-mentioned member and to each other and each having upwardly extending marginal walls, angular guides secured to the first-mentioned base member adapted to separate the relatively movable slideable members and serve as a guide therefor, a plate-like holding member having marginal walls extending downwardly to guide the slideable members, and extensible means supported by the slideable members of the base adapted to support the work.

37. In a typewriting machine, a carriage base comprising a relatively fixed member having marginal upwardly extending walls lengthwise thereof, two plate-like slideable members movable relatively to the first-mentioned member and to each other and each having upwardly extending marginal walls, a plate-like holding member having marginal walls extending downwardly to guide the slideable members, means for locking the slideable members in different positions, and extensible means supported by the slideable members of the base adapted to support the work.

38. In a typewriting machine, a carriage base comprising a relatively fixed member having marginal upwardly extending walls lengthwise thereof, two plate-like slideable members movable relatively to the first-mentioned member and to each other and each having upwardly extending marginal walls, and means supported by the slideable members of the base adapted to support the work.

39. In a typewriting machine, a carriage base comprising a relatively fixed member having marginal upwardly extending walls lengthwise thereof, two plate-like slideable members movable relatively to the first-mentioned member and to each other and each having upwardly extending marginal walls, means for locking the slideable members in various positions, means for moving said slideable members in opposite directions, and a platen supported by the slideable members.

40. In a typewriting machine, a carriage, a platen roll having a main body portion rotatably supported in the carriage, paper fingers cooperating with the main body por-

tion, extensible platen roll end sections, and work retaining means coöperating with said sections and movable therewith.

41. In a typewriting machine, a carriage, 5 a platen roll having a main body portion rotatably supported in the carriage, extensible platen end sections, and work retaining means coöperating with said sections.

42. In a typewriting machine, the combination of an extensible carriage, an extensible platen roll rotatably supported in said carriage at its ends, means coöperating with the platen to assist in holding the work thereto a part of said means being extensible, feeding means coöperating with the platen roll, a scale located adjacent to the platen roll and unaffected by the extension thereof, means for releasing the paper feed means, line-spacing means, a rack mounted 20 upon the carriage, and escapement releasing means also mounted on the carriage and unaffected by the extension of the carriage or platen roll sections.

43. In a typewriting machine, the combination of an extensible carriage, an extensible platen roll rotatably supported in said carriage at its ends, feeding means coöperating with the platen roll, and means for releasing the paper feed means.

44. In a typewriting machine, the combination of an extensible carriage, an extensible platen roll rotatably supported in said carriage at its ends, means coöperating with the platen roll to assist in holding the work 35 thereto a part of said means being extensi-

ble, feeding means coöperating with the platen roll, and means for releasing the paper feed means.

45. In a typewriting machine, the combination of an extensible platen carriage, a 40 platen rotatably supported on the carriage, and line spacing means maintained in co-operative relation with the platen when said carriage is extended or contracted.

46. In a typewriting machine, the combination of an extensible work-sheet support, means for supporting the work-sheet support in extended or contracted condition, and line spacing means maintained in operative relation to the extensible work-sheet 50 support in the extended or contracted positions thereof.

47. In a typewriting machine, a carriage having extensible platen-supporting means, and a platen rotatably mounted in said extensible supporting means and having its support therein maintained in all positions of said extensible means.

48. In a typewriting machine, a carriage having a base member, two lengthwise movable plate-like slidable members, end brackets arranged on said slidable members, means whereby the slidable members may be guided and held, and a platen supported in the brackets.

This specification signed this 4th day of January A. D. 1916.

BENJAMIN W. TUCKER.
JAMES A. EKIN CRISWELL.
